UNITED STATES PATENT OFFICE.

HENRY IEVERS, OF NEW YORK, N. Y.

DESIGN FOR A GAS-FLAME SPREADER.

SPECIFICATION forming part of Design No. 32,955, dated July 17, 1900.

Application filed June 21, 1900. Serial No. 21,113. Term of patent 7 years.

To all whom it may concern:

Be it known that I, HENRY IEVERS, a subject of the Queen of Great Britain, residing in New York, in the county of Richmond and 5 State of New York, have invented and produced a new and original Design for a Gas-Flame Spreader, of which the following is a specification, reference being had to the accompanying drawings, forming part thereof.

As shown in the drawings, the leading or material features of my invention consist of 5 the body 10 and the parallel laterally-extending members 11 thereof, together with the generally-circular top 12 and the recess or opening 13 in the under part of the top, said recess or opening having the irregular top line, as shown. The flat body portion 10 is slightly reduced, as shown at 10^a, and merges in the generally-circular top 12, which when viewed in elevation has the outline of a large segment of a circle, the bottom portion of the circle being cut away or recessed, as at 13, 25 which recess has an irregular top line formed by the two side cuts 14 and the central curved line 15. The recess or cut-away portion 13 is made in practically the central portion of the top 12.

Having thus described my invention, what I claim as new, and desire to secure by Letters Patent, is—

The design for a gas-flame spreader as herein shown and described.

In testimony whereof I have signed my name to this specification in the presence of two subscribing witnesses.

HENRY IEVERS.
